COMPARTMENTED PACKAGING TRAY

Hugh R. Weiss, Montclair, N.J., assignor to The Pantasote Company, Passaic, N.J., a corporation of New Jersey

Filed Dec. 23, 1964, Ser. No. 83,141

Term of patent 14 years

(Cl. D58—13)

FIGURE 3 is a fragmentary rear side elevational view showing one half of the article, the other half being the same in appearance;

FIGURE 4 is an end elevational view on a larger scale, the end opposite being the same in appearance as the end shown;

I claim:

The ornamental design for a compartmented packaging tray, as shown and described.
